UNITED STATES PATENT OFFICE.

ALBERT A. CARPER, OF BALTIMORE, MARYLAND, ASSIGNOR TO THE CROWN CORK AND SEAL COMPANY OF BALTIMORE CITY, OF BALTIMORE, MARYLAND, A CORPORATION OF MARYLAND.

PACKAGING APPARATUS.

1,271,432.

Specification of Letters Patent.

Patented July 2, 1918.

Application filed December 31, 1913. Serial No. 809,616.

To all whom it may concern:

Be it known that I, ALBERT A. CARPER, a citizen of the United States, residing at Baltimore and State of Maryland, have invented certain new and useful Improvements in Packaging Apparatus, fully described and represented in the following specification and the accompanying drawings, forming a part of the same.

10 This invention relates to improvements in means for feeding containers.

One general object of the invention is to provide a feeding device which will reliably feed containers such as bottles to a machine 15 which is to perform some operations in connection with such containers, as for example a machine for filling said containers, or a machine for applying closures to them.

A further object of the invention is to 20 provide means for feeding containers to a closure applying machine, so that it becomes possible to use a compact and relatively small closure applying machine with loading means of large capacity and still have the 25 closure applying machine successively handle and apply closures to all the containers delivered thereto.

With these general objects in view, the 30 invention consists in the features, details of construction and combination of parts which will first be described in connection with the accompanying drawings and then be particularly pointed out.

In the drawings,

35 Figure 1 is a vertical section partly in elevation of a mechanism embodying the best form of the invention;

Fig. 2 is a plan view partly broken away of the mechanism shown in Fig. 1;

40 Fig. 3 is an enlarged detail view partly in section of the discharge mechanism;

Fig. 4 a horizontal section in the line 4—4 Fig. 1;

Fig. 5 a detail sectional view partly in 45 elevation of the capping mechanism;

Fig. 6 a plan view of the bottle neck guideway;

50 Figs. 7 and 8 enlarged detail views partly in section showing the discharge mechanism in different positions, and

Figs. 9, 10 and 11 detail sectional views of the discharge mechanism.

While the particular construction of 55 crowning mechanism employed in carrying the invention into effect may be varied,

that selected for the purpose of illustrating the invention is substantially the mechanism illustrated in the Painter Patent No. 638,354. Referring to the drawings, 1 indicates a hopper into which the crowns are thrown in a mass, the crowns being delivered, by a suitable selecting mechanism not necessary to describe, to a plurality of rotating crowning heads 2, these heads successively registering with and receiving 60 crowns from a chute 3 leading from the hopper referred to. To attain the proper positioning of the bottles beneath said heads, a bottle neck guide 2' is attached to the heads as shown in Figs. 5 and 6, this being necessary 65 with a quick-running machine. The machine also includes a rotating carrier, as 4, this carrier being supported upon and rotating around a stationary central post 5. While, as has been indicated, the devices 70 by which the crowning is effected may be varied in construction, in the particular mechanism illustrated, the carrier serves to support a plurality of reciprocating lifting plungers 6. As shown, these plungers are 75 provided with anti-friction wheels 7 which run on a track-cam 8 having a rise 9, indicated in dotted lines in Fig. 1, which is so located as at the proper time to cause the bottles to be lifted and their tops forced into 80 capping heads 2, these heads being supplied with the usual bending dies which attach the crowns. The plungers are 85 enclosed by a housing, as 6', and this housing serves to support a table 7' for receiving the 90 filled bottles, this table being cut away as clearly shown in Fig. 2 to receive the top of the carrier 4. The mechanism which has been herein described is substantially that illustrated and described in the Painter Patent No. 638,354, above referred to, to which reference may be had for a detailed description of the construction. Also, to insure the proper positioning of the bottles in their respective supports, a yielding 95 presser device is provided as shown at 65, this being arranged to crowd the bottles into their respective supports, as will be clear from the drawings.

For the purpose of transporting containers, such as bottles, from a loading point which may, for example, be the discharge point of a filling machine to the capping machine, a suitable transporting mechanism is employed, this consisting in the best em- 105 110

bodiment of the invention of a conveyer arranged to transport bottles by mere frictional engagement with the bottles, said conveyer having a capacity such that it may serve as 5 a storage space for containers intermediate the loading point and the capping machine. In order to render this storage space effective for the purpose intended, the said conveyer or transporting device should run at 10 a speed greater than corresponds to the rate of loading of containers at the loading point. That is to say, the conveyer tends to remove a container very rapidly from the loading point so that such a container tends 15 to be carried immediately to a point remote from the point of loading. Means are provided adjacent the capping machine for positively discharging the containers from the advanced end of the transporting device to 20 the respective bottle supports of the capping machine. This means for discharging the containers is not continuously operated although it is arranged to be operated by the capping machine and in a certain fixed 25 relation thereto, but is held out of operation by a suitable trip mechanism arranged to be released by the arrival of a container in a predetermined position where it actuates said tripping mechanism to release the 30 means for discharging containers, which thereupon can be operated by the capping mechanism in proper timed relation to sweep a container from the point where it operated the tripping device into the corresponding 35 bottle support on the capping machine. By this arrangement, it is possible to carry on the operation of loading and capping independently of each other, provided, however, that the capping machine be run at 40 such a speed that it can cap containers faster than the loading operation can deliver them. Consequently, by this arrangement, if at any time it becomes necessary to stop the capping machine for a brief interval, 45 such as usually suffices to make any adjustment which might be required, the containers which are delivered by the continued loading operation at that time may be allowed to accumulate on the transporting 50 device, so that the operation of the loading need not be interrupted. Then the capping machine may be started up and run at a rapid speed, whereby it will cap containers faster than they are being delivered by the 55 loading means and hence will soon catch up with the work done by the loading means and thus reduce the supply of bottles which have accumulated on the transporting device. Of course, it will be understood that 60 the length of time which the capping machine may be shut down while the loading means is operating depends entirely on the capacity of the transporting device. An important feature of the invention is that there 65 is permitted the use of a rotary capping

machine, the number of whose capping heads is not necessarily an aliquot part of the number of filling heads on any filling machine should the latter be used in connection with the capping machine.

In the specific embodiment of the invention illustrated in the drawings, the transporting device comprises a traveling platform,—in this case formed as a rotating table 37 having a hub 38 secured to a vertical shaft 39 journaled at its lower end in a bracket 40 secured to the housing 6' of the capping machine, the shaft 39 being provided with a worm-wheel 41 engaged by a worm 42 on a worm-shaft 43, also suitably 70 journaled, as for example in the said bracket, and provided at its inner end with a pinion 44 driven by a crown gear 45 arranged to rotate with the rotary bottle-lifting devices of the capping machine. The rotating table 37 is mounted beneath a stationary cap-plate 46 (Fig. 2) which is suitably secured to the work table 7' by bolts as shown in Fig. 2, this cap plate having an up-turned flange 47 serving as a guide which is formed 75 as a compound curve and acts in conjunction with a corresponding guide formed as an upturned flange 48 of a rim 49, to guide the containers from the loading point to the capping machine. The rim 49 is suitably 80 secured to the table 7' as by bolts. The guide 47 is provided with an extension 50 which serves to guide the containers to the container pathway between the guides 47, 48. At the end of the container pathway 85 nearest the capping machine, the flange 47 is deflected in a direction substantially transverse to the direction of travel of the containers in the pathway at that point, thus forming a fixed abutment, as indicated 90 at 47'. The corresponding opposite edge of the flange 48 terminates sufficiently short 95 of the flange 47 to leave a lateral opening through which the containers may be discharged from the transporting mechanism 100 past the abutment to the respective bottle supports 36 of the capping head. For the purpose of sweeping the containers from the transporting mechanism through this lateral opening into the bottle support at 105 that time in proper position to receive the respective container, a suitable discharge mechanism is employed consisting in the present example of a discharge arm 51 located 110 in a recess in the stationary cap plate and secured to a vertical shaft 52, which is provided with a crank arm 53 carrying a roller 54. The roller is normally but yieldingly pressed toward the outer periphery of a suitable cam path 4' on the rotating portion of the capping machine by suitable 115 spring mechanism, as for example the spring 55, secured to an arm 56 connected to the shaft 52. In the present example, the roller 54 engages the periphery of the rotating car- 120

rier 4, which periphery, in cross section, comprises a wavy surface arranged to oscillate the roller 54 and its crank arm 53, together with the shaft 52, to a certain amplitude, once for each cap head carried by the capping machine.

The spring 55 tends to move the discharge arm inwardly to a distance sufficient to discharge a container from the container path 10 way into the respective container support carried by the capping machine, whenever the roller 54 is permitted to ride down into the bottom of a recess in the cam surface of the rotary carrier. However, the discharge 15 arm is normally held against the action of the spring 55 so that the roller 54 cannot be forced by said spring into the deepest parts of the cam recess. The means for holding the discharge arm comprises a tripping device having a member located in the path of travel of the containers, said tripping device normally holding the discharge arm from swinging in a direction to discharge a container, but being arranged so 20 that when tripped by the arrival of a container in connection with its tripping member, the discharge arm will be released and then can be moved by the spring 55 in a direction to sweep the container into a bottle 25 support at the time when the roller 54 comes opposite a corresponding recess in the cam surface. In the present example, this tripping mechanism comprises a lever having one arm 57 extending into the path of the 30 container at a position nearer the discharge end thereof, as will be clear from Figs. 2 and 7, the lever being pivoted at 57' to the bottom of the recess in the cap plate. On the same pivot 57' is mounted a swinging 35 40 latch 58 having a notch at one end arranged to engage a pin 59 projecting downward from the underside of the discharge arm 51. The latch 58 is connected by a spring 60 to the tripping lever 57 and the said tripping lever is yieldingly held with its tripping end in the path of travel of the containers by means of the spring 61 attached to said lever 57 and to a pin 61' projecting upward from the bottom of the recess in 45 50 the cap plate. The lever 57 also has a downward extending lug 62 arranged to bear against one side of the latch 58 so that when the said tripping lever 57 is pulled by the tension spring 61 so as to hold its outer end 55 in the path of travel of the containers, the said spring 61 will thereby also serve to hold the latch 58 in line with the pin 59, a suitable stop 63 being secured to the bottom 60 of the recess in the cap plate. By this means, the engagement of the pin 59 in the notch of the latch 58 will prevent the discharge arm 51 from being swung to the bottle supports of the capping machine by the spring 55. At this time when the pin 59 is fully seated in the notch of the latch

58, the roller 54 is in engagement with a portion of the cam surface slightly below the highest point of such surface, as indicated at Fig. 7. As the roller 54 comes onto the highest point of such cam surface, the discharge arm is moved slightly backward against the action of the spring 55 so that the pin 59 carried by said discharge arm will be freed from the notch in the latch 58, but, with the tripping device 57 in its normal position, the latch 58 is held by the spring 61 tightly against the stop 63 and therefore as the roller 54 rides off a highest point of the cam, it will not be able to travel into one of the lowest points of said cam because 80 the pin 59 will travel back into the notch in the end of the latch 58 under the action of the spring 55. When, however, a container, as indicated for example at 64, Fig. 7, is moved by the rotating table 37 against 85 the outward end of the tripping lever 57, the said outer end is swung forward by said container 64 and thereby the spring 60 is extended, thus tending to pull the latch 58 away from the stop 63, which tendency 90 is prevented by the pin 59 at that time in the notch in the end of the latch. As soon, however, as the discharge arm is swung slightly away from the bottle supports by the arrival of a high point of the cam surface beneath the roller 54, as hereinbefore explained, the pin 59 is freed from the notch and the latch is then immediately pulled by the tension of the spring 60 until the parts have a position as indicated in Fig. 7, whereby the discharge arm 51 is freed and tends to move toward the bottle supports of the capping machine under the influence of the spring 55 when permitted to do so by the travel of the roller 54 into the deepest part 95 of the cam recess. Consequently, any container which has pushed the outer end of the tripping lever into a position to release the discharge arm, will be moved by the discharge arm at the proper time, from the 100 transporting mechanism into the bottle support of the capping machine at that time in proper position to receive a container. As the cam surface moves beneath the roller 54, the next point of the cam will swing the 105 discharge arm backward away from the bottle support. Thereafter the lever 57 and with it the latch 58 will be pulled back into their normal position to again latch the discharge arm. The latch 58 has its outer end 110 provided with an upward extending lug 58', whose inner surface is inclined so that the pin 59 by engaging said inclined surface may swing the latch lever so as to enable the pin to reach its position behind the end 115 of the latch lever so as to be ready to engage the notch in the end of the same.

The operation of the device is obvious from the explanation hereinbefore given, but may be briefly described as follows: 130

Bottles may be loaded onto the extension of the path for the containers, as, for example, by the guide arm 50'. The bottom of this extension portion is stationary and hence the bottles are conveyed along this portion of the path merely by the crowding in of one bottle after the other. As soon, however, as the bottles reach that portion of the path which is over the rotating carrier 37, the bottles are moved rapidly ahead along the path of the containers at a speed which advantageously is greater than merely necessary for removal of bottles being loaded. That is to say, the tendency of the bottles is to be shot forward rapidly to the discharge end of the transporting device, this tendency, of course, being overcome where the path of travel for the container is entirely filled with bottles as, for example, when the capping machine is not in operation. The arrival of the forward container at the discharge end of the transporting device trips the lever 57 as hereinbefore explained and prepares the discharge arm for operation by the cam of the capping machine which acts on the roller 54. Upon the arrival of the proper bottle support 36 of the capping machine in a position to receive a container, the discharge arm is operated in the manner hereinbefore described to sweep the forward container into said bottle support. Thereupon, the discharge arm is returned and the tendency of the springs 60, 61, is to again lock the discharge arm and bring the outer end of the lever 57 into the path of travel of the containers. If, however, a container has already been moved up to its extreme forward position, immediately upon the discharge of the prior container, the lever 57 will be retained in its unlatching position and the discharge arm will again operate at the proper time for discharge of said next container into the next succeeding bottle support. This operation of discharging bottles will proceed so long as the bottles continue to arrive immediately one after the other at the discharge end of the transporting device. If, however, owing to the fact that the capping machine is running faster than the rate of bottle supply, and owing to the speed of the transporting device, all the bottles on the transporting device have been capped, or no bottle has arrived at the discharge end of the transporting mechanism, the lever 57 will swing into the path of travel of the containers and the discharge arm will be locked by the latch. No movement of said discharge arm in the direction toward the capping machine will take place until the arrival of a bottle against the trip lever.

From this, it will be seen that the capping machine may at any time be speeded up to cap all the bottles at that time ready for

capping on the transporting device, and then may be stopped for the purposes of any adjustments or the like for the short time necessary to enable the loading operation to again fill the transporting device with bottles. This is a great convenience, because it enables the parts of the capping machine to be lubricated or adjusted while said capping machine is stationary, and as this can be quickly done, it is usually unnecessary to shut down the bottle supply. Furthermore, by this arrangement, there need be no relation between the number of capping heads on the capping machine and the number of filling heads on any filling machine which may be combined with the capping machine, as is required in those cases where it is necessary to operate two machines in a certain fixed relation. Moreover, the disadvantage of the latter operation, namely, that, due to wear of gearing and the like, frequent adjustments and replacements of parts are necessary, is entirely avoided.

What is claimed is:

1. The combination, with a rotary capping mechanism having a cam surface provided with a high and a low portion for each capping head, an oscillating discharge arm arranged to be actuated from said cam surface of the capping mechanism, a conveyer arranged to transport the bottles toward the said capping mechanism, and means for holding the discharge arm out of operation, said means having a member arranged to be actuated by the contact of a bottle therewith and thereby to release the discharge arm.

2. The combination, with a closure applying mechanism, of a transporting means for transporting containers to the closure applying mechanism, said transporting means comprising a discharge apparatus, means actuated by said closure applying mechanism for operating said discharge apparatus, and means for preventing the operation of said discharge apparatus, said preventing means being arranged to be released by the containers.

3. The combination, with a closure applying mechanism, of a carrier arranged to carry bottles to the capping mechanism, a discharge device arranged to discharge bottles from the carrier into the capping mechanism, means located in the path of the bottles and arranged to hold said discharge mechanism out of action, and means operated by the capping mechanism for actuating said discharge mechanism.

4. The combination, with a capping mechanism, of a conveyer arranged to transport bottles toward the capping mechanism, a fixed abutment in the path of said bottles and arranged to stop their forward movement, and means controlled by the bottles

for discharging the bottles past said abutment.

5. The combination, with a capping mechanism, of a traveling platform arranged to transport bottles toward the capping mechanism, a fixed abutment in the path of said bottles and arranged to stop their forward movement, and means controlled by the bottles for discharging the bottles past said

10 abutment.

6. The combination, with a capping mechanism, of a conveyer arranged to transport bottles to one side of the capping mechanism, a fixed abutment arranged to stop said bottles at a point adjacent the capping mechanism, an oscillating arm arranged to sweep said bottles past the abutment and into the bottle supports of the capping mechanism, means for operating said discharge mechanism in timed relation with the capping mechanism, and means for holding said discharge mechanism from operation, said holding means having a member ar-

ranged to be engaged and released by the respective bottles as they reach the abut- 25

7. The combination, with a capping mechanism, of a conveyer arranged to transport bottles toward the capping mechanism, a trip lever located at the forward end of the 30 conveyer, an oscillating discharge mechanism arranged to be actuated in timed relation with the capping mechanism, a latch device arranged to lock the discharge mechanism, and means intermediate the trip lever 35 and the latch device whereby the discharge mechanism is unlocked upon the arrival of a bottle in contact with the trip lever.

In testimony whereof, I have hereunto set my hand, in the presence of two subscribing 40 witnesses.

ALBERT A. CARPER.
